UNITED STATES PATENT OFFICE.

JOHN KORIZON, OF ATLANTA, GEORGIA.

TILE-FORMING MACHINE.

Application filed July 21, 1924. Serial No. 727,371.

To all whom it may concern:

Be it known that I, JOHN KORIZON, a citizen of the United States, residing at Atlanta, in the county of Fulton and State of

5 Georgia, have invented certain new and useful Improvements in Tile-Forming Machines, of which the following is a specification.

This invention relates to tile manufacture and has special reference to a tile molding machine particularly adapted for the manufacture of terrazzo tiles suitable for floor and wall coverings and the like.

One important object of the invention is 15 to provide a novel general construction of machine for this purpose wherein the material used for filling the molds is constantly jarred or shaken during the pressing operation.

20 A second important object of the invention is to provide an improved arrangement of presser roll actuating means in such a machine.

25 A third important object of the invention is to provide an improved knocker operating mechanism for machines of this type.

30 A fourth important object of the invention is to provide a multiple mold tile machine having a novel jarring arrangement wherein the material in each of the several molds will receive individual jarring.

35 With the above and other objects in view as will be hereinafter apparent, the invention consists in general of certain novel details of construction and combinations of parts hereinafter fully described, illustrated in the accompanying drawings and specifically claimed.

40 In the accompanying drawings like characters of reference indicate like parts in the several views, and:

Figure 1 is a plan view of the machine.

Figure 2 is a side elevation thereof.

Figure 3 is an end view thereof.

45 Figure 4 is a vertical section through the section of the roller carriage and showing the roller in elevation.

Figure 5 is a detail of the hammer drive.

50 Figure 6 is another detail part of the hammer drive.

Figure 7 is a modified arrangement of hammers.

55 In the embodiment of the invention herein disclosed it will be seen that there is provided a frame 10 which supports a longitudinally extending mold carrying table or

platens 11. At each side of the platen and substantially on the level therewith is a guide rail 12 and on these rails run the wheels 13 of a pair of oppositely disposed carriages 14 each of which is provided at its upper portion with a suitable bearing 15 to receive the journal portion of a roll carrying shaft 16. On the shaft 16 between the bearings is fixed a pressing roller 17 the bottom of which is spaced above the platen 11 to permit the roller to run on the upper surface of the reticulated mold 18 resting on a mold bottom plate 19 which is preferably of thin metal and rests on the 60 platen 11, being properly positioned thereon by engagement with lugs 20.

At the rear end of the frame is a pair of bearings 21 wherein is journalled a shaft 22 which extends transversely of the frame 75 and projects beyond the sides thereof to carry the rear end idler pulleys 23. Similarly there is provided at the front of the frame transverse shafts 24 which carry the idler pulleys 26. The ends of the shaft 80 16 project in like manner and are provided with belt pulleys 27 which are positioned above respective pairs of carriage idlers 28 running freely on the stub shafts 29 fixed to the carriages 14. A belt 30 is provided on each side of the machine which is led around the various pulleys in the manner shown in the drawings and which may be described as from one pulley 26 beneath one of the pulleys 28, up and over the pulley 27, down and beneath the other pulley 28, rearwardly and around the rear idler pulley and thence back to the other idler 26. It will be noted that, with this arrangement, the presser roller will be rotated irrespective of the position of the carriages so long as the shaft 24 is driven.

90 To drive the belt there is provided in front of the frame a pair of bearings 31 wherein is journalled a jack shaft 32 which carries a belt pulley 33 around which the belt 30 passes. Furthermore the shaft 32 has revolubly mounted thereon a spaced pair of pulleys 36 provided with confronting clutch faces 37 between which is a double clutch member 38, this clutch member 100 being splined on the shaft so that it may be moved by the shipper lever 39, which engages therewith, into clutching engagement with one or the other of the pulley clutch faces and thereby rotate the jack shaft. In front of this jack shaft is a main shaft 40

supported in bearings 41 and driven from some suitable source of power not deemed necessary here to be shown. On the main shaft 40 is keyed a pair of pulleys 42 one of which is connected by a straight belt 43 with one of the pulleys 36 while the other pulley 42 is connected with the remaining pulley 36 by a cross belt 44. Thus by shifting the clutch the jack shaft can be driven in one direction or the other and this in turn will drive the presser roll in corresponding directions.

In order to effect automatic reversal of the presser roll after it has moved from the front to the rear of the machine a lever 45 is pivoted to the frame at the rear and has its upper end projecting into the path of one of the carriages 14 so that, upon the carriage approaching the rearward limit of its movement, it will strike this lever and shift the same. Thus lever 45 is furthermore connected to the shipper lever by a linkage 46 so that movement of the lever 45 effects movement of the shipper lever. These parts are so proportioned that the movement of the shipper lever disengages the central clutch member from one clutch face and engages it with the other.

In the operation of this part of the device the mold is placed on the platen and the clutch thrown in the proper direction to cause the roller, which at the start is slightly in front of the mold, to roll rearwardly upon its being started by moving the carriages back until the roller engages the mold. Then the roller rolls backward and runs over the mold pressing the mold contents down in the mold. Upon the carriage striking the lever 45 the rotation is reversed and the roller moves forward until it rolls off the mold whereupon the forward motion stops as the roller no longer contacts with any surface to roll thereover, the roller shifting the clutch to neutral position at the same time.

The knocking or jarring mechanism comprises a lower longitudinal shaft 47 journaled in bearings 48 and carrying at its forward end a bevel gear 49 which meshes with a bevel gear 50 keyed on a jack shaft 50'. On the shaft 47 are also fixed belt pulleys 51 which are connected by belts 52 with pulleys 53 on the cam shafts 54. In the main form of the device each cam shaft is provided with a series of cam wheels 55 each having a plurality of cam projections 56. Preferably there is one cam shaft for each two longitudinal rows of molds and each cam shaft has a cam wheel for each transverse row of molds in the multiple mold. Parallel with each cam shaft is a fixed shaft 57 whereon is mounted a series of oscillatable spring hammers 58 equal in number to the cams and actuated by the cam projections, those hammers being so arranged that each strikes its blows centrally beneath a re-

spective mold. The shafts 57 may be adjusted to regulate force of the blows by moving them toward or from the cam shaft and this may also be effected by adjustment of the stop pins 59 in the slots 60 formed in the plates 61 which may be carried by the fixed shafts 57. Thus there is one hammer for each individual mold and the rotation of the cam shafts causes oscillation of the hammers and effects a continuous series of blows beneath the molds.

In the modified form of the device the hammer shafts are journaled in suitable bearings and the hammers fixed thereon so that but one cam is needed on the respective cam shaft, the engagement of the projections of this cam with one hammer actuating the entire set for the particular hammer shaft.

To drive the jack shaft 50' a belt 62 connects this shaft with the main shaft 40, the usual pulleys being employed.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a tile molding machine, a platen, a knocker mechanism beneath said platen and operative to strike a series of blows on the under side thereof, a roller for traversing the platen above the same, and means for actuating said knocker mechanism and cause the roller to traverse said platen.

2. In a tile machine, a mold supporting platen, rails at the sides of said platen, carriages mounted on said rails to travel therealong, a roller supported revolvably by said carriages to pass over a mold on said platen, a knocker mechanism adapted to strike said platen, a shaft carrying means to operate the knocker mechanism and means to rotate said shaft and said roller and thereby simultaneously knock the platen and cause the roller to move over said mold.

3. In a tile machine, a mold supporting platen, rails at the sides of said platen, carriages mounted on said rails to travel therealong, a roller supported revolvably by said carriages to pass over a mold on said platen, a driving pulley adjacent one end of the platen, a driven pulley on said roller, an idler pulley adjacent the other end of the platen, a belt extending around said pulleys, a pair of idler pulleys supported on one of said carriages and arranged to maintain a constant tension on said belt in all posi-

- tion of the roller on said platen, a jack shaft having operative connection with the driving pulley, a pair of driven clutch members revolving on the jack shaft in opposite directions, a third clutch member cooperating selectively with said pair, a shipper lever controlling the position of the third clutch member, a reversing lever having one end in the path of one of said 10 carriages, and an operating linkage connecting the reverse and shipper levers.
4. In a tile machine, a mold supporting platen, a hammer shaft extending beneath said platen, hammers on said shaft arranged to strike the under side of the platen upon actuation, a cam mechanism engaging and actuating the hammers, and means to actuate the cam mechanism.
5. In a tile machine, a mold supporting platen, a hammer shaft extending beneath said platen, hammers on said shaft arranged to strike the under side of the platen upon actuation, said hammers being swingingly mounted on said shaft, a cam shaft parallel to the hammer shaft, cams fixed on said cam shaft each engaging and operating a hammer, means to drive said cam shaft, and means to control the force of the blows struck by said hammers.
- 15 6. In a tile machine, a mold supporting platen, a hammer shaft extending beneath said platen, hammers on said shaft arranged to strike the under side of the platen upon actuation, a cam shaft parallel to the hammer shaft, cams fixed on said cam shaft each engaging and operating a hammer, means to drive said cam shaft, and means to control the force of the blows struck by said hammers including adjustable stop pins for regulating the limit of movement of the hammers in one direction, and means to hold the pins in adjusted positions.
- 20 7. In a tile machine, a mold supporting platen, a hammer shaft extending beneath said platen, hammers on said shaft arranged to strike the under side of the platen upon actuation, said hammers being swingingly mounted on said shaft, a cam shaft parallel to the hammer shaft, cams fixed on said cam shaft each engaging and operating a hammer, means to drive said cam shaft, and means to control the force of the blows struck by said hammers including adjustable stop pins for regulating the limit of movement of the hammers in one direction, and means to hold the pins in adjusted positions.
